UNITED STATES PATENT OFFICE.

JOHNSTON MEALEY, OF HOWARD, MINNESOTA.

DESIGN FOR A BUCKLE.

SPECIFICATION forming part of Design No. 27,169, dated June 8, 1897.

Application filed March 16, 1897. Serial No. 627,905. Term of patent 7 years.

To all whom it may concern:

Be it known that I, JOHNSTON MEALEY, a citizen of the United States, residing at Howard, in the county of Wright and State 5 of Minnesota, have invented and produced a new and original Design for a Splicing-Buckle, of which the following is a specification, reference being had to the accompanying drawings, forming a part thereof.

Figure 1 is a perspective of a splicing-buckle constructed in accordance with my design. Fig. 2 is a longitudinal section of the same.

The leading feature of my design consists in the sides A, having oppositely-turned ends, 5 the cross-bars B, connecting the extreme ends of the sides A, and similar cross-bars C

upon opposite sides of the frame connecting the angles formed by the oppositely-turned ends.

The design also includes pins or lugs D on 20 the inner surface of the cross-bars C and extending in opposite directions.

I claim as my invention—

The design for a splicing-buckle substantially as shown and described. 25

In testimony whereof I have hereunto set my hand this 18th day of November, A. D. 1896.

JOHNSTON MEALEY.

In presence of—

C. G. HAWLEY,
RICHARD PAUL.
